(57) **CLAIM**

The ornamental design for a face plate for computer housing, as shown and described.

DESCRIPTION

FIG. 1 is a perspective view of a face plate for computer housing showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the face plate for computer housing in use.

The broken line environmental showing is for illustrative purpose only and forms no part of the claimed design.
